UNITED STATES PATENT OFFICE.

RALPH C. SEYMOUR, OF LARCHMONT, NEW YORK, ASSIGNOR, BY MESNE ASSIGNMENTS, TO C. B. COTTRELL & SONS COMPANY, OF NEW YORK, N. Y., A CORPORATION OF NEW JERSEY.

ASSOCIATING AND BINDING MACHINE.

1,048,357.

Specification of Letters Patent. Patented Dec. 24, 1912.

Application filed June 10, 1908. Serial No. 437,731.

To all whom it may concern:

Be it known that I, RALPH C. SEYMOUR, a citizen of the United States, and residing at Larchmont, in the county of Westchester 5 and State of New York, have invented certain new and useful Improvements in Associating and Binding Machines, of which the following is a specification.

The invention relates to machines for 10 operating upon printed sheets or webs to put them into book or pamphlet form.

Objects of the invention are to provide 15 for rapidly, efficiently and economically associating a plurality of printed sheets and a cover and performing all other steps thereon necessary to produce a book or pamphlet; to provide for positive handling of the material at high speed so that a product of excellent and uniform quality is 20 secured; to provide for rapid handling of the material as regards the speed of operation of the various parts or members of the machine; to provide mechanisms capable of 25 performing a plurality of operations upon the material at one time; to provide a machine realizing the various objects of invention and which is of simple and compact structure. These and other objects of invention will in part be obvious and will in part 30 more fully appear herein.

The invention consists in the novel parts, arrangements, combinations and improvements herein shown and described.

The accompanying drawings, referred to 35 herein and forming a part hereof, illustrate one embodiment of the invention, the same serving in connection with the description herein to explain the principles of the invention.

40 Of the drawings: Figure 1 is a vertical section on the line A—B of Fig. 2 of a machine constructed in part in accordance with the principles of the invention; Fig. 2 is a plan thereof; Fig. 3 is a sectional plan on the line C—D of Fig. 1; and Figs. 4, 5, 6, 7 and 8 are fragmentary views showing different positions of various mechanisms.

50 Referring to the accompanying drawings, illustrating by way of example one embodiment of the invention, means for associating printed sheets and a cover are disclosed. The form of such means illustrated herewith is adapted to coöperate with a single web or a plurality of webs and is 55 shown as receiving from a printing press

or other suitable source webs 1 and 2 which are directed into the machine by suitable means, as by passing between friction rolls 3 and 4. Means for severing the webs into sheets are provided and in the illustrated 60 embodiment the sheets pass between cutting cylinders 5 and 6. A throat is shown adjacent to the cutter rolls consisting of a series of bars 7 and 8 for suitably directing the fed-in web. 65

The associating means, in its illustrated form, is shown as comprising devices for collecting the sheets severed from the web, the form thereof herein shown comprising a cylinder 9 provided with suitable grippers 70 10 for taking the ends of the webs, and as the webs are severed by the cutters 5 and 6, the severed sheets will pass around the cylinder 9. Additional collecting devices may be employed and in the illustrated embodiment a second cylinder 11 is shown adjacent to the cylinder 9 which also engages the webs and gathers the sheets as severed therefrom by the cutting devices. The cylinder 11 is also designed to take the sheets 80 from cylinder 9 and associate them with the sheets which it takes directly from the web. 75

Means for supplying covers are also contemplated by the invention in some of its 85 aspects. So far as concerns certain aspects thereof, a cover may be supplied in various ways as by feeding in as shown, for the webs, by associating it with one of the webs, or otherwise, or the cover might be omitted. 90 In the illustrated embodiment of the invention and according to certain features thereof it is intended to supply one or more covers to one of the sheet taking devices, as the cylinders 9 and 11, so as to associate 95 the sheets and cover and then to forward them through the machine for binding and folding and any other desired operations. Accordingly in the present embodiment a form of such means is shown. As herein shown, the covers are supplied to the cylinder 11. Said covers may be supplied by hand, or by a suitable automatic mechanism, or otherwise, no particular form thereof being shown herein. Conveying devices 100 may be employed for bringing the covers forward into position to be taken by the cylinder 11 and the illustrated form thereof comprises conveying tapes 12 running on the rollers 13. Front gages or stops 14, 110

which may be of a well-known form, are shown for the purpose of positioning the fed cover and for permitting it to pass to the grippers of the cylinder 11 when they 5 are in position to take the cover.

If it is desired to sever the covers prior to association thereof with the sheets, suitable means therefor may be provided, although this is immaterial so far as concerns 10 many features of the invention. A form of such means is shown herein comprising a fixed knife 17 below the plane of the covers as they are fed in between the conveyer tapes 15 mounted upon the rolls 16, and a 15 reciprocating knife 18 mounted upon a cross-head 20 working in guides 19 upon the press frame. To operate the movable knife 18, there is shown a groove cam 21 with which a suitable arm 22 from the cross-head 20 engages to give a reciprocating motion to the knife 18.

Suitable devices for taking the cover and also for taking sheets are provided on the cylinder 11 and are shown herein as two 25 series of grippers 23 and 24, respectively, which are operated in a suitable manner and at proper times as will be well understood by those skilled in the art. One set of grippers is designed to take the covers as 30 they pass the front gage 14 and the other set of grippers to engage the downwardly feeding ends of the webs 1 and 2. The sheets upon the cylinder 9 are also transferred to the cylinder 11, as hereinbefore 35 indicated, so as to give a plurality of superimposed sheets associated with each other and with a cover.

Means are contemplated by the invention for binding the sheets and cover together 40 into a book or pamphlet and according to certain features of the invention it is further contemplated to separate the associated sheets and cover into a plurality of books or pamphlets. In certain of its aspects, furthermore, the invention contemplates binding and separating the associated sheets and cover simultaneously, or substantially simultaneously. Certain features of the invention 45 also contemplate providing a form of combined binding and separating, or slitting, mechanism in which the binding and slitting devices may perform their respective functions upon the associated sheets and cover at one operation thereby conducting to 50 rapidity of operation and excellence of product as will be more fully pointed out hereinafter. The form of such means shown herein comprises binding devices 25, designed for stapling or wire stitching. The 55 specific form thereof is not shown in detail, such devices being known in the art. Said devices may be operated in any suitable manner to wire stitch the sheets and cover presented thereto in successive sets from the 60 associating means for the successive binding 65

operations. Said mechanisms are shown herein connected for operation by miter gears 26 with a suitably driven shaft 27.

The form of means for separating the associated sheets into a plurality of books or pamphlets, that is, in the present embodiment for slitting same, comprises a plurality of sets of knives relatively movable with respect to each other and each set shown herein as comprising a fixed knife 28 and a 70 reciprocating knife 29. The knives 28 are shown mounted upon suitable supports 30 and 31. The reciprocating knives 29 are shown mounted upon a suitable frame 32 75 slidable in ways 33 in the machine frame. Means are provided for actuating the knives 29, together with their supporting frame, and the form thereof herein shown comprises suitably shaped cams 34 mounted upon a rotatable shaft 35. Anti-friction 80 rolls 36 are shown engaging grooves in the cams 34, said rolls being fixed to the frame 32.

Guiding tapes 37 and 38 are shown passing around the cylinder 11 for guiding the 90 associated sheets and cover to the binding and slitting mechanism. A suitable surface 39 is provided for holding the sheets to the stapling device during the binding and slitting operation.

Suitable devices are provided for positioning the associated sheets and cover for binding and slitting and in the present embodiment a form of such means is provided in connection with means for engaging or 100 gripping the several slit sections in the binding the slitting position and for then positively moving them into position to be engaged by the folding devices. So far as concerns many features of the invention, 105 however, these two means may be arranged to operate independently of each other. As shown herein registering stops 40 serve to position the sheets as shown in Fig. 8 of the drawings. Said stop is shown mounted 110 upon a jaw 41 fixed to the cross-head 42; its companion jaw 43 is shown pivoted to the cross-head at 44 and as having connected thereto a tripping arm 45. A suitable 115 spring may be used for holding the jaws 110 normally to the closed position in a well-known manner. The cross-head 42 is shown mounted upon guides 46 in the machine frame for reciprocation between the position for registering the associated sheets and 120 cover for the binding and slitting operations and the folding position. Suitable cam faces 47 and 76 are shown for opening the gripper at its receiving position and its delivering position, respectively. Means 125 for reciprocating the gripper and its cross-head to and fro are provided and the form thereof herein shown comprises links 48 pivoted to the cross-head and to levers 49 mounted upon the machine frame. Anti- 130

friction rolls 50 are shown upon the levers 49 engaging with groove cams 51 carried upon a suitably driven shaft 52.

Suitable folding devices are contemplated by the invention and certain features thereof contemplate a set of folding jaws operating from above down on to a folding blade to fold the sheets thereover and then to carry them away therefrom upwardly. The sheets are thus carried freely through the atmosphere instead of being passed through rolls or drawn through a slot. The invention in certain of its aspects contemplates also a plurality of folding mechanisms acting respectively on successive sets of the slit sheets and cover. That is, one set of sheets with their cover having been slit and bound is acted upon by a folding mechanism and the next set is acted upon by another folding mechanism. Certain features of the invention contemplate further providing a folding blade and folding jaws co-operating therewith to fold the cover over the sheets. As illustrated herein a fixed folding blade 53 is shown which may be located adjacent to the binding and slitting mechanisms. A plurality of sets of folding jaws are provided, each moving into operative relation with said blade from above, so that in its turn it will fold a set of sheets with their cover over the blade and then carry same upwardly therefrom and deliver them to a suitable receiving device. As illustrated herein two arms 54 are shown fixed to a shaft 55 mounted on the machine frame. Mounted on said arms is shown a fixed jaw 56 and a movable spring-pressed jaw 57. A suitable tripping arm 58 is also shown connected to the jaw 57. Fixed to the shaft 55 are shown two arms 59 connected by pivoted links 60 to levers 61. The other end of said levers is shown in operative relation with cams 62 fixed upon a rotatable shaft 63. A pair of arms 64 is also shown pivoted to the frame, respectively, at 65. Fixed to said arms 64 is shown a jaw 66 and in operative relation therewith a movable spring-pressed jaw 67. Connected to said jaw is also shown a tripping arm 68. Suitable means for actuating said arms are provided and herein geared sectors 69, one fixed with reference to each of the arms 64, are shown in mesh with geared sectors 70 carried by the shaft 55. It will be seen by reference to Fig. 1 that the binding means and folding means are arranged at one side from the associating means and are further arranged with respect to the other mechanisms to afford free access thereto from above for cleaning, adjustment, and other necessary operations.

Suitable delivery devices are provided and according to certain features of the invention said folding devices are constructed and arranged to deliver their prod-

ncts at the same point or to the same delivery mechanism. As illustrated herewith a series of pocket deliveries 71 are shown upon a suitable conveyer 72 passing over rolls 73 and driven in any suitable manner. Cam shapes 74 and 75 are shown for the purpose of acting on the tripping arms 58 and 68, respectively, to open the folding jaws in the delivery position.

The manner of operation of the herein-described mechanism is substantially as follows: The webs 1 and 2, feeding down between the feed rolls 3 and 4, the ends thereof are engaged by the grippers 10. The rotary cutters 5 and 6 then act to sever the end portions of the web into sheets which pass around the cylinder 9, the rolls 76 serving to hold the sheets upon the cylinder. The cover is fed down through the tapes 12 and 15 to the front gage 14. As the cylinder 11 rotates the grippers thereon engage the cover and the front stop 14 lifts to allow the cover to pass. As the cylinder 11 continues to rotate the other ends of the webs 1 and 2 are taken by the grippers 90 thereon and at or about the same time the cylinder 9 delivers its sheets thereto, the associated sheets and cover then passing onward, as shown in Figs. 1, 4, 5 and 8 of the drawings, to the binding and slitting 95 position, the cover being on top.

The bundle or set of sheets with their cover are positioned or registered by the gage 40 and the knives 29 are operated by their cams 34 and the connected mechanism 100 to sever the associated sheets and cover. At the same time the wire stitchers operate to stitch each of the severed parts, thus binding the sheets and cover together. The cams 51, through levers 49 and their connections, then start the grippers 41-43 into motion and, the tripping arm 45 slipping off the cam 47, grippers 41-43 close upon each of the severed sections, engaging them positively and carrying them over to the folding position, as shown in Figs. 6 and 7 of the drawings. The associated sheets and cover are brought to rest above and in proper register with respect to the fixed folding blade 53 and one of the sets 110 of folding jaws is swung downwardly and folds the cover over the sheets as shown in Fig. 7 of the drawings, operating simultaneously upon all the sections. The folding jaws are then swung upwardly by their arms into the delivery position where either the cam shape 74 or 75, as the case may be, serves to open the jaws and deliver the sheets into the delivery pockets 71, as shown in Fig. 7 of the drawings.

The sets of folding jaws are geared to move down alternately into the folding position and back to the delivery position, as will be clearly understood from the foregoing description. One set of arms passes to 130

and from within the other set of arms, their jaws at the same time passing within the other set of jaws, but each being centered with respect to the folding blade and coming into suitable delivery position with respect to the receiving devices 71. In the meantime the cycle of operations herein described is again under way and is repeated successively, as will be clearly understood, 10 while the machine continues to operate.

Where it is desired to feed a large sheet and sever same, the cutters 17 and 18 will operate to cut the cover and as the first part is fed out the second part will be fed down 15 to the front stops 14.

It will be understood that the timing of operations is not necessarily precisely as stated nor as shown in the drawings here-with, as changes in the timing of the parts, 20 as well as kindred changes which may con-
duce to harmonious action of the mech-
anism are within the skill of ordinary me-
chanical designers. The description and
examples given will, however, serve to make
25 clear to those skilled in the art the prin-
ciples of the invention and the general oper-
ation of the present embodiment.

From all the foregoing it will be under-
stood that a machine has been provided em-
30 bodying the principles of the invention and
which realizes the objects of invention
and the advantages herein set forth together
with other objects and advantages.

The invention, in its broader aspects, is
35 not limited to the particular constructions
shown, nor to any particular constructions
by which it has been or may be carried into
effect, as many changes may be made in the
construction without departing from the
40 main principles of the invention and with-
out sacrificing its chief advantages.

What I do claim as my invention and de-
sire to secure by Letters Patent, is:

1. An associating and binding machine
45 including in combination means for associ-
ating printed sheets and a cover, binding
means, and separating means constructed
and arranged to simultaneously bind and
separate said sheets and cover into a plu-
50 rality of books.

2. An associating and binding machine
including in combination means for associ-
ating printed sheets, slitting means and
55 binding means located contiguously to each
other, and means for simultaneously position-
ing the sheets for binding and slitting.

3. An associating and binding machine
including in combination means for associ-
ating printed sheets, slitting means and
60 binding means located contiguously to each
other, and means for simultaneously operat-
ing said slitting means and said binding
means.

4. An associating and binding machine
65 including in combination means for associ-

ating printed sheets, means for binding
them together, and a folding blade and fold-
ing jaws co-operating therewith to fold the
bound sheets and carry them freely there-
from.

5. An associating and binding machine
including in combination means for associ-
ating printed sheets, means for binding
them together, a fixed folding blade and re-
ciprocating folding jaws co-operating there-
70 with to fold the bound sheets and carry them
75 freely therefrom.

6. An associating and binding machine
including in combination means for associ-
ating a plurality of sheets, binding and slit-
ting means constructed and arranged to op-
erate upon the associated sheets substan-
80 tially simultaneously, and a plurality of
folding mechanism acting respectively on
successive sets of the slit and bound sheets.
85

7. An associating and binding machine
including in combination means for associ-
ating a plurality of sheets, binding and slit-
ting means constructed and arranged to op-
erate upon the associated sheets substantially
90 simultaneously, and means for folding at
one time all the slit and bound sections pro-
duced by one operation of said binding and
slitting means.

8. An associating and binding machine
95 including in combination means for associ-
ating a plurality of sheets, binding and slit-
ting means constructed and arranged to op-
erate upon the associated sheets substantially
100 simultaneously, and a plurality of folding
mechanisms acting respectively on suc-
cessive sets of the slit and bound sheets, said
mechanisms being constructed and arranged
to all deliver the folded sheets at the same
point.

9. An associating and binding machine in-
cluding in combination means for associat-
ing a plurality of sheets, binding and slit-
ting means constructed and arranged to op-
erate upon the associated sheet substantially
110 simultaneously, a plurality of folding mech-
anisms acting on successive sets of the slit
and bound sheets, and means for engaging
said sheets at the binding position and mov-
ing them to the folding position.

10. An associating and binding machine
including in combination means for associ-
ating a plurality of sheets, binding and slit-
ting means constructed and arranged to op-
erate upon the associated sheets substan-
120 tially simultaneously, a plurality of folding
mechanisms acting on successive sets of the
slit and bound sheets, said mechanisms being
constructed and arranged to all deliver the
125 folded sheets at the same point, and means
for engaging said sheets at the binding po-
sition and moving them to the folding po-
sition.

11. An associating and binding machine
including in combination, means for asso-
130

- ciating a plurality of sheets, binding devices for binding the sheets together, folding devices, and gripping devices for gripping the sheets at the binding position and positively moving same into coöperative relation with the folding devices.
12. An associating and binding machine including in combination means for associating a plurality of sheets, binding devices for binding the sheets together, a folding blade and folding jaws coöperating therewith, and gripping devices for gripping the sheets at the binding position and positively moving same into coöperative relation with the folding devices.
13. An associating and binding machine including in combination means for associating a plurality of sheets, binding devices for binding the sheets together, a fixed folding blade and traveling folding jaws coöperating therewith, and gripping devices for gripping the sheets in the binding position and moving them into definite relation with the fixed folding blade.
14. An associating and binding machine including in combination means for associating a plurality of sheets, folding devices, means for positioning the associated sheets, means for binding and slitting the positioned sheets, and means for engaging the bound and slit sheets and moving them into definite relation with the folding devices.
15. An associating and binding machine including in combination means for associating a plurality of sheets, a folding blade and folding jaws coöperating therewith, means for positioning the associated sheets, means for binding and slitting the positioned sheets, and means for engaging the bound and slit sheets and moving them into definite relation with the folding blade and folding jaws.
16. An associating and binding machine including in combination means for associating a plurality of sheets, a fixed folding blade and movable folding jaws coöperating therewith, means for positioning the associated sheets, means for binding and slitting the positioned sheets, and means for engaging the bound and slit sheets and moving them into definite relation with the folding blade preparatory to their being folded thereover by the folding jaws.
17. An associating and binding machine including in combination means for associating a plurality of sheets, means for conveying them into position for binding, binding means, means for registering the associated sheets in position for binding, means for gripping the associated sheets when in said registered position and moving them to the folding position, and folding means for folding the sheets.
18. An associating and binding machine including in combination means for associating a plurality of sheets, means for conveying the sheets from the place of slitting to the place of folding, said means having grippers which grip the sheets at the place of slitting and convey them together to the place of folding, and means for simultaneously folding the sections.
19. An associating and binding machine including in combination means for conveying the sheets to the slitting means, means for slitting the associated sheets, means for simultaneously engaging all of the slit sections at the place of slitting, and moving them together to the folding position, and means for folding said sections.
20. A machine for binding a plurality of sheets into a book which includes in combination a slitting device and a binding device arranged transversely of each other and further arranged to operate simultaneously upon a plurality of associated sheets.
21. The combination with a pair of slitting knives, one knife of the pair reciprocating to and from the other, of stapling devices arranged contiguous thereto, and means for operating the slitting knife and the stapling devices simultaneously.
22. The combination with a plurality of pairs of slitting knives, one knife of each pair being reciprocable with respect to the other, of a plurality of stapling devices adjacent to said knives and arranged transversely thereof, and means for operating said devices, said parts being constructed and arranged so that the slitting and binding operations are performed simultaneously.
23. The combination with a fixed folding blade of a plurality of sets of folding jaws, said sets of folding jaws passing successively into operative relation with said folding blade.
24. The combination with a fixed folding blade of a plurality of sets of folding jaws, said sets of folding jaws passing successively into operative relation with said folding blade and arranged to deliver the folded product at the same place.
25. An associating and binding machine including in combination means for associating a plurality of sheets, a pair of longitudinally arranged knives, transversely arranged stapling devices, a stop for positioning the associated sheets in operative relation to said devices, a fixed folding blade, grippers for engaging the slit sections in said position and for positively moving same into position with said fixed folding blade, a plurality of traveling folding jaws coöperating successively with said folding blade to simultaneously fold said slitted and bound portions, and means for receiving same from the folding jaws.

26. An associating and binding machine including in combination means for directing a web into the machine web cutting devices, a cylinder for collecting sheets from the web, a second cylinder for collecting sheets from said web and from said first-mentioned cylinder, means for feeding a cover sheet directly to said second cylinder, binding devices and folding devices for operating upon the bound sheets to fold them into a book. 10
27. An associating and binding machine including in combination means for directing a web into the machine web cutting devices, a cylinder for collecting sheets from the web, a second cylinder for collecting sheets from said web and from said first-mentioned cylinder, automatic means for feeding a cover to one of said cylinders, binding devices and folding devices for operating upon the bound sheets and cover to fold them into a book. 15
28. A machine for folding sheets including in combination a folding blade, reciprocating folding jaws coöoperating therewith to fold without cutting the sheets, means for moving said jaws upwardly to carry away the folded sheet, and means for receiving the folded sheet from the jaws when so moved upwardly. 25
29. A machine for folding sheets including in combination a fixed folding blade, a set of folding jaws, mounted upon a swinging carrier, and coöperating from above to fold a sheet over said blade and then to lift it away from the blade. 35
30. An associating and binding machine including in combination means for associating printed sheets and a cover, means for binding them together, and a traveling device for folding the book and delivering it upwardly. 40
31. An associating and binding machine including in combination means for associating printed sheets and a cover with the cover on the upper side, traveling means for folding the cover over the sheets and for delivering the folded book upwardly. 45
32. An associating and binding machine including in combination means for associating printed sheets and a cover and delivering same to a folding device with the cover on the upper side, a folding device having a fixed folding blade below the sheets and cover, and a folding jaw operating from above to fold the book over the said folding blade and to carry it away upwardly to deliver it. 50
33. An associating and binding machine including in combination means for supplying the sheets, a registering device, means for supplying a cover to said sheets including means for feeding up a cover sheet to said registering device, separating it into two parts, feeding off one part to the sheets and then feeding up the other part of the cover to said registering device, to associate same with succeeding sheets. 55
34. A binding machine including in combination a plurality of parallel slitting knives, a plurality of stapling devices arranged in a row between the knives and intermediately their ends, and means for operating the knives and staplers simultaneously. 70
35. A binding machine including in combination a slitting knife, a stapling device at either side of the knife and intermediate its ends, and means for simultaneously operating the knife and staplers. 75
36. A binding machine including in combination binding means, means for conveying sheets thereto, a stop for bringing the sheets to rest in position for binding thereby, and means for gripping the stopped sheets and conveying them away. 80
37. A binding machine including in combination binding means, means for conveying sheets thereto, a stop for bringing the sheets to rest in position for binding thereby, folding means, and means for gripping the sheets at rest at the binding position and for moving and bringing them to rest in position for folding by the folding means. 85
38. A binding machine including in combination binding means, means for conveying sheets thereto, a stop for bringing the sheets to rest in position for binding thereby, a folding blade, means for engaging the sheets at rest at the binding position and for moving and bringing them to rest in position for folding, and traveling folding jaws for folding the sheets over the folding blade and carrying them away. 90
39. An associating and binding machine including in combination web directing means, web cutting means, a cylinder for collecting sheets from the web, a second cylinder for collecting sheets from said web and from said first mentioned cylinder, binding means, receiving means for the bound sheets and means which engage the bound sheets to fold and carry them by the fold to the receiving means. 100
40. An associating and binding machine including in combination sheet and cover supplying and associating means, binding means located at one side therefrom so as to have a free space for access from above, and traveling folding means located at one side from the other mechanisms for folding the bound sheets and delivering them upwardly. 110
41. An associating and binding machine including in combination sheet associating means, means for directing a web thereto from above, traveling folding means located at one side from said associating means and arranged to fold the associated sheets and carry them freely upwardly. 125

42. An associating and binding machine including in combination sheet associating means, means for directing a web thereto from above, binding means located below and at one side therefrom to receive and bind the associated sheets and traveling folding jaws beside the binding means for folding the bound sheets and delivering them freely upwardly. 55
- 10 43. An associating and binding machine including in combination means for associating a plurality of sheets, means for registering the sheets prior to binding; means for firmly gripping the registered sheets, means for binding the registered and gripped sheets, and means for positioning the sheets for folding while so gripped and means for folding the sheets. 60
- 15 44. An associating and binding machine including in combination means for associating a plurality of sheets, means for conveying the sheets to the slitting position, means for stopping the sheets in slitting position, means for slitting the associated sheets, means for moving the slit sections to the folding position and means for folding said sections; the slitting moving and folding means being arranged to give a straight path of travel to the sheets from the associating means to the folding means. 65
- 20 45. An associating and binding machine including in combination means for associating a plurality of sheets, means for slitting the associated sheets, grippers which grip the slit sheets at the slitting position to move them to the folding position, said grippers remaining closed upon the sheets during said entire movement, and means for folding said slit sheets. 70
- 25 46. A sheet handling machine including in combination means for conveying a sheet, binding means, folding means, a device which stops and registers the sheet at the binding means and then grips and conveys it from said binding means to said folding means. 75
- 30 47. A sheet handling machine including in combination means for conveying the sheets along a straight path, a plurality of means arranged along said straight path for operating upon the sheets, a device which reciprocates to and fro along a portion of said straight path, said device having means for arresting and positioning the sheets in operative relation with one of said means for operating upon the sheet, and also having means for gripping the sheets and conveying them to another of said operating means. 80
48. A folding machine including in combination a folding blade, sheet receiving means, a pair of jaws and a pair of arms swinging and reciprocating about a center to carry the jaws between the folding blade and sheet receiving means, said pair of jaws being mounted on said arms to fold a sheet over the blade and carry it away and deliver it to said sheet receiving means. 85
49. A folding mechanism including in combination a folding blade, sheet receiving means, a pair of folding jaws and a carrier swinging and reciprocating about a center to carry the jaws between the folding blade and sheet receiving means, said pair of folding jaws being mounted on said carrier which fold a sheet over the blade and carry it away and deliver it to said sheet receiving means. 90
50. In a folding machine, a folding table, a fixed folding blade, a set of reciprocating folding jaws arranged to coact with the folding blade from above the table and means for bringing the sheets into position on the folding table over the folding blade. 95
51. In a folding machine, a folding table, a folding blade, a set of reciprocating folding jaws, arranged to coact with the folding blade from above the table and means reciprocating in substantially right lines for bringing the sheets into position on the folding table. 100
52. In a folding machine, a delivery carrier, a folding table, a fixed folding blade, means for bringing the sheets into position on the folding table over the folding blade, and a set of reciprocating folding jaws arranged to coact with the folding blade from above the table for folding the sheets and transferring them to the delivery carrier. 105
- In testimony whereof, I have signed my name to this specification, in the presence of two subscribing witnesses.
- RALPH C. SEYMOUR.
- Witnesses:
- JOHN D. MORGAN,
KATHARINE SEXTON.
